UNITED STATES PATENT OFFICE.

WILLIAM MILLER, OF ST. LOUIS, MISSOURI, ASSIGNEE TO ACME PIPE CLAMP COMPANY, OF ST. LOUIS, MISSOURI, A CORPORATION OF ILLINOIS.

TRAIN-PIPE CLAMP.

1,030,200.

Specification of Letters Patent. Patented June 18, 1912.

Application filed January 2, 1912. Serial No. 668,917.

To all whom it may concern:

Be it known that I, WILLIAM MILLER, a citizen of the United States, residing at St. Louis, Missouri, have invented a certain new and useful Improvement in Train-Pipe Clamps, of which the following is a full, clear, and exact description, such as will enable others skilled in the art to which it appertains to make and use the same.

10 This invention relates to train pipe clamps such as are used on railway cars for supporting and holding the train pipe in position.

One object of my invention is to provide 15 a device of the character referred to in which the coöperating members are connected together in such a manner that there is no liability of their becoming separated when the device is opened up to receive the 20 train pipe.

Another object is to provide an inexpensive 25 train pipe clamp of novel construction in which the coöperating members are locked together in such a manner that there is no possibility of the device opening up accidentally and thus releasing the train 30 pipe.

Other objects and desirable features of 35 my invention will be hereinafter pointed out.

Figure 1 of the drawings is a front elevational view of a train pipe clamp constructed in accordance with my invention; Fig. 2 is a side elevational view of the clamp; Fig. 3 is a front elevational view of a combined angle cock and pipe clamp constructed in accordance with my invention; and Fig. 4 is a front elevational view of a slightly modified form of my invention.

40 Referring to the drawings which illustrate the preferred form of my invention, A and B designate two members provided with coöperating semi-ring-shaped portions 1 that form a sleeve which receives the train pipe C, the stationary member A being provided at its upper end with an arm or extension 1^a through which fastening devices 2 pass so as to secure the clamp to the car. The members A and B are preferably 45 formed from cast metal, and the movable member B is provided at its lower end with an integral hook 3 which is of less width than the semi-circular-shaped portion 1 of said member so that said hook will fit freely 50 between a pair of integral ears 4 on the

member A that carry a pin 5 which the hook 3 partly surrounds. To eliminate the possibility of the members A and B becoming detached when the clamp is opened up to receive the pipe I have provided the hook 60 on the member B with an extension 3^a that is adapted to be bent around the pin 5 on the member A, from the position shown in broken lines in Fig. 1 into the position shown in full lines in said figure, after said 65 members have been assembled. The extension 3^a on said hook is so proportioned that the space between the end of same and the portion of the member B directly opposite said extension is less than the diameter of 70 the pin 5. Consequently, after the extension 3^a has been bent around the pin 5, the lower ends of the members A and B will be securely locked together in such a manner that there is no possibility of the movable member 75 dropping off when it is swung downwardly to receive the pipe C. A pipe clamp of the construction above-described is inexpensive to manufacture and assemble, and it is just as efficient as a pipe clamp in 80 which a pintle or removable pivot pin is inserted through coöperating perforated ears on the two members of the clamp for after the extension 3^a on the hook 3 has been bent over into its final position the lower 85 ends of the members A and B are permanently hinged together.

The upper or free end of the movable member of the clamp is preferably locked in position by means of a key that passes 90 through a lug on one member of the clamp that projects through an opening in the other member of the clamp. In the form of my invention shown in Fig. 1, the stationary member A of the clamp is provided 95 with a laterally projecting lug 6 that passes through an opening 7 in the upper end of the movable member B of the clamp, and a key, preferably a wedge-shaped cotter key 8, is inserted in an opening 9 in said lug 100 so as to extend cross-wise of the movable member B and thus prevent it from moving outwardly away from the stationary member A of the clamp. I prefer to curve the lug 6 downwardly slightly, as shown in Fig. 105 1, so that it will not interfere with the swinging movement of the member B but this is not absolutely essential for the lug 6 could be made straight and so proportioned that it did not interfere with the 110

member B. Instead of providing the stationary member of the clamp with a lug for holding the locking key, as above-described, the movable member B of the clamp could be provided with a lug 6^a that passes through an opening in the stationary member of the clamp, as shown in Fig. 4. The locking key 8 can be inserted and withdrawn easily, and after it has been arranged in operative position there is no danger of its becoming displaced and thus releasing the train pipe. Therefore, such a pipe clamp is a decided improvement on the train pipe clamps now in general use which are provided with a nut and bolt for holding the movable member of the clamp in its closed position.

In Fig. 3 I have shown a combined angle cock and pipe clamp constructed in accordance with my invention, the two coöperating members A' and B' of the clamp being provided with two oppositely disposed forwardly extending projections 10 which are shaped on their inner opposing faces to engage opposite angles on the hexagonal head of the angle cock, not shown, which the device supports.

Having thus described my invention, what I claim as new and desire to secure by Letters Patent is:

1. A combined angle cock and train pipe

clamp comprising two members hinged together at one end and provided with co-operating semi-ring-shaped portions that embrace the pipe, oppositely disposed lugs 35 projecting forwardly from said portions for engaging the head of the angle cock, a laterally projecting part on one member that passes through an opening in the other member at a point above the train pipe, and a 40 removable key in said laterally projecting part that extends transversely across the member through which the part projects.

2. A combined angle cock and train pipe clamp comprising two cast metal members 45 provided with coöperating pipe-engaging portions and integral portions for embracing the head of an angle cock, an integral hook on one of said members that engages a pin formed integral with the other member, an extension on said hook that is adapted to be bent over said pin so as to lock said members together, and means that prevent the clamp from opening.

In testimony whereof I hereunto affix my 55 signature in the presence of two witnesses, this twenty ninth day of December 1911.

WILLIAM MILLER.
